UNITED STATES PATENT OFFICE.

PAUL WAGNER, OF CULBERTSON, MONTANA.

FLUE-CUTTER.

1,160,019.

Specification of Letters Patent.

Patented Nov. 9, 1915.

Application filed July 17, 1914. Serial No. 851,532.

To all whom it may concern:

Be it known that I, PAUL WAGNER, a citizen of the United States, residing at Culbertson, in the county of Sheridan and State of Montana, have invented new and useful Improvements in Flue-Cutters, of which the following is a specification.

The present invention relates to improvements in cutting devices primarily intended for use in connection with boiler flue pipes, the primary object being to simplify and improve the existing art by providing a device of this character which shall embody the desirable features of simplicity of construction, cheapness in manufacture, and efficiency and accuracy in operation.

With the above and other objects in view, the improvement resides in the construction, combination and arrangement of parts set forth in the following specification and falling within the scope of the appended claim.

In the drawings: Figure 1 is a view illustrating the application of my improvement to a boiler flue, the flue pipe being shown in section, Fig. 2 is a similar view, a portion of the stock of the cutter being shown in section and the cutting wheel moved into operative engagement with the flue, Fig. 3 is an end view of the improvement. Fig. 4 is a central longitudinal sectional view through the same. Fig. 5 is an end elevation of a stock, the cutter and fulcrum wedge being removed, Fig. 6 is a detail perspective view of the spring arm showing the cutter wheel journaled thereon, and Fig. 7 is a perspective view of the combined rest and adjusting member for the spring arm of the cutter wheel. Fig. 8 is a detail perspective view of the inner stock member.

Referring now to the drawings in detail, the numeral 1 designates a tube comprising a boiler flue, the same being secured to the end plates 2 but having its end formed with the usual angular flange or bead 3 which contacts with said plate adjacent to the opening through which the tube 1 passes.

My improved cutter is generally designated by the numeral 4 and embodies essentially a tubular stock 5 which is of a less cross sectional diameter than the interior of the flue tube 1. The stock may be made up of two sections 6 and 7 respectively, as illustrated in the drawings, one end of the section 6 having an interior

threaded enlargement or sleeve 8 which receives the threaded end of the section 7, the section 7 in turn having its second end provided with a sleeve 9, similar to the sleeve 8 and both of the sleeves 8 and 9 have a plurality of openings 10 arranged radially of the central axial plane thereof. When only the section 6 is employed, the openings 10 are adapted to receive a fulcrum member, which fulcrum member is inserted within one of the openings 10 of the sleeve 9 of the section 7 when the stock is made up of two sections.

The opposite end of the tubular section 6 is provided with a longitudinally extending slot or opening 12, and the opposite walls provided thereby being slotted transversely at the end wall of the said slot and at a suitable distance from the end of the tube 6, as indicated by the numerals 13, and the metal between the slits is extended inwardly of the tubular members 6, providing guide walls 14 and 14' which engage with the opposite sides of a substantially rectangular head 15 formed upon the end of a spring arm 16. The arm 16 is arranged at an angle to its head and its free end is also provided with an angular portion 17 having a threaded opening 18, the same being secured within the member 6 through the medium of a headed bolt 19 which has its shank passing through a suitable opening in the said member 6 and is received by the threads in the opening 18. The arrangement of the spring is such that the head 15 will be normally sustained within the member 6 and not projected through the opening 12, and the tension of the spring is also exerted in this direction, so that the head 15 will not be projected through the said opening 12 except when forced in such direction, in a manner which will presently be described.

The head 12 is arranged upon one of the faces of the spring arm 16, which may be termed the outer face, and the said head is centrally slotted to provide the same with a pair of spaced arms, each of which has a longitudinally extending registering opening 20 which receives the shaft or trunnion 21 of a cutter wheel 22, the said cutter wheel being disposed between the said arms of the head and is, with the head, normally sustained in the members 6. The numeral 23 designates a collar which is arranged upon the stock 5, the same having an adjusting

screw 27 whereby the longitudinal movement of the said collar may be regulated, and the same properly positioned with relation to the cutter wheel 22.

5 Arranged within the stock is a combined rest and adjusting member for the spring arm 16 of the cutter wheel, the same comprising a wedge-shaped member 28 having its reduced end formed with a longitudinally 10 extending threaded shank 29. In the present instance, the shank 29 is connected with a longitudinally extending threaded rod 30 through the medium of a suitable sleeve or nut 31, the end of the rod 30 having ar- 15 ranged thereon a disk 32 which closes the open end of the stock, a nut 33 being ar- ranged upon the threaded rod, the same bearing against the disk 32 to provide means for longitudinally adjusting the wedge 20 member 28, so that the same may be brought inwardly of the stock to force the head 15 and the cutter wheel 22 out of the opening 12. This operation permits of the wedge- 25 shaped member being fulcrumed against the interior surface or end of the tubular stock, so that the wedge obtains a purchase for the performance of its function.

From the above description, taken in connection with the accompanying drawings,

the simplicity of the device, as well as the 30 advantages thereof will, it is thought, be perfectly apparent to those skilled in the art to which such invention appertains without further detailed description.

Having thus described the invention, what 35 I claim is:

In a flue cutter, the combination of a hollow stock having a spring member provided with an angular head secured therein, a longitudinal wedge-shaped fulcrum member 40 upon which the spring member rests, and a cutter wheel arranged upon the angular head of the spring, said stock being provided with a longitudinal opening in one of its ends to receive the head of the spring, 45 the adjacent walls provided by the opening at the terminal of the said opening and at a distance from the said terminal being slotted laterally and the portions between the slits being bent toward each other to contact with 50 the opposite sides of the spring head to provide guides therefor.

In testimony whereof I affix my signature in presence of two witnesses.

PAUL WAGNER.
